UNITED STATES PATENT OFFICE.

NICHOLAS MARCALUS, OF PLAINFIELD, NEW JERSEY.

WEB-WINDING MACHINE.

Application filed August 18, 1925. Serial No. 50,903.

This invention relates to web-winding machines. More particularly, it relates to a machine in which a web of paper, cloth or other flexible material is unwound from a parent roll, slit into units of the desired width, wound upon tubes or cores fed to the machine, perforated, glued and discharged. There are no machines at present in use for performing all of these operations. According to the best practice prior to my invention, the operator places the tubes or cores about which the material is to be wound, upon a spindle, places the spindle in the machine, wraps by hand several turns of the material from the parent roll about the core and starts the machine, which then winds and slits by motive power. When the desired quantity has been wound, the operator stops the machine, breaks the paper along the width of the web, glues the end of the rolls, and removes the spindle from the machine. This operation is repeated for each set of rolls. In my copending application, Ser. No. 624,357, I have disclosed and claimed an automatic winding and wrapping machine. This machine is provided with three sets of rollers, which are automatically rotated in predetermined sequential combinations. One set, the winding and wrapping rollers hold and rotate the core and wind the material about it, slitting the material into sheets of appropriate widths at the same time. A second set, the feeding rollers, feed the material to the core from the parent roll and cooperate with a perforator to perforate it at the end of the winding. When the desired length of material has been wound about the core, the feeding rollers stop, while the winding rollers continue to rotate. This tears the material along the perforation and separates the wound roll from the web. Thereupon a third set of rollers, the wrapper rollers, feed a wrapper to the winding rollers, cooperate with a perforator to perforate the wrapper after a predetermined length has been fed, and automatically apply glue to it. When the wound roll has been wrapped, the wrapper rollers stop and the winding rollers continue to rotate, thus tearing the wrapper along the perforation and detaching it from the wrapper web. The winding rollers then continue to rotate long enough to tighten the wrapper about the roll and ensure the

adhesion of the glue. Thereupon the winding rollers separate to discharge the wound and wrapped roll, and a new core is fed into place. The operation is then repeated.

In accordance with the present invention I have provided a somewhat modified form of machine for producing an unwrapped wound roll. The machine of the present invention is provided with novel means for applying adhesive to the web itself just before the end of the winding operation, the feeding of the web continuing just long enough after this to permit the glued portion of the web to come in contact with the wound roll. When this contact has been made the feeding and winding are automatically arrested, one of the winding rollers swings out of supporting position and an ejector severs the web adjacent the wound roll and forces the latter out of the machine.

A preferred embodiment of the invention is clearly illustrated in the accompanying drawings, in which:

Figure 1 is a front elevation of the novel machine made according to and embodying the principles of my present invention; Figure 2 is a transverse vertical section through the machine, taken on the line 2-2 in Figure 1; Figure 3 is a fragmentary longitudinal vertical section through the machine, taken on line 3-3 in Figure 2; Figure 4 is a fragmentary elevation of one end of the machine; Figure 5 is a detail fragmentary horizontal section, taken on line 5-5 in said Figure 1, said view being drawn on an enlarged scale; Figure 6 is a detail vertical transverse section, taken on line 6-6 in said Figure 5; Figure 7 is another transverse vertical section, taken on line 7-7 in said Figure 5; Figure 8 is a fragmentary transverse vertical section, taken on line 8-8 in Figure 3, drawn on an enlarged scale, and Figure 9 is a similar view, the former view showing the normal initial inoperative condition of the gluing device and the latter view showing the operative condition of the same; and Figure 10 is a perspective view of a wound roll of paper as produced by the machine.

Similar characters of reference are employed in all of the hereinabove described views, to indicate corresponding parts.

Referring now to said drawings, the reference character 11 indicates a pair of stand-

ards or end frame members for supporting the operative parts of the mechanism, said standards or end frame members being longitudinally spaced apart, but interconnected by longitudinal tie-rods 12. Extending outwardly from the front side of each standard or end frame member 11, adjacent to its lower end, is a bearing bracket 13 upon which is supported a mandrel 14. Mounted upon said mandrel 14 is the delivery roll 15 of paper web 16 which is to be operated upon by the machine.

Mounted upon a shaft 17, journaled in and extending longitudinally between said standards or end frame members 11, is a perforator bed roller 18, having in its circumferential face longitudinally extending grooves or channels 19. Mounted upon a shaft 20, also journaled in and extending longitudinally between said standards or end frame members 11, is a combined feed and guide roller 21 paralleling the forward side of said perforator bed roller 18.

Journaled in and extending between said standards or end frame members 11, so as to be situated in the rear of said perforator bed roller 18, is a group of winding rollers, comprising an upper winding roller 22, a forward lower winding roller 23 and a rearward lower winding roller 24, which are preferably spaced apart at one-hundred and twenty degree intervals about a circular line intersecting their axes. Said forward lower winding roller 23 also constitutes a slitting roller, the same being provided with annular cutting blades 25 having serrated or saw-toothed cutting edges which are affixed to the roller so as to project from the circumference thereof, and which are secured to the roller in longitudinally spaced relation corresponding to the widths of the runs to which it is desired to reduce the paper web 16. Mounted above said combined forward lower winding and slitting roller 23 is a slitting bed roller 26 annularly grooved at points opposed to said cutting blades 25. Said rearward lower winding roller 24 also constitutes a gate roller, in that it is supported so as to be capable of swinging bodily away from its normal operative relation to the winding rollers 22 and 23, for purposes to be subsequently more fully explained. The means for mounting the combined winding and gate roller 24 to permit of such swinging movement comprises a rock shaft 27, upon the ends of which are secured arms 28 provided at their free ends with bearing members 29 to receive the journals 30 of said winding and gate roller 24. Extending from one of the bearing members 29 is a lever arm 31 provided at its free end with an anti-friction roller 32 engageable by an actuating mechanism to be hereinafter described; and extending from the other or opposite bearing member 29 is a lever arm

33, to which is attached a pull-spring 34 which tends to yieldably hold said winding and gate roller 24 in normal operative position. Said winding and gate roller 24 may be suitably counterbalanced by providing the rock shaft 27 with forwardly extending lever arms 35 affixed thereto, and from the free ends of which are suspended counterbalance weights 36. A carrier tube feeding means is provided in the rear of said group of winding rollers, the same being so disposed that its discharge mouth terminates at a point intermediate the upper winding roller 22 and the combined winding and gate roller 24. This tube feeding means comprises a runway or stacker frame 37 for supporting the tubes 38 in a train one above the other. Journaled in and extending between said standards or end frame members 11, below and adjacent to the discharge end of said stacker frame 37 is a shaft 39 upon which are fixed detent starwheels 40 for normally engaging and detaining the lowermost tube 38 against discharge until the detent starwheels are actuated. Fixed on one end of said shaft 39 is an actuator or tripper starwheel 41 for actuating said shaft 39 and its detent starwheels 40; the means for in turn actuating the tripper starwheel 41 will be subsequently described.

Journaled in and extending between said standards or end frame members 11, above said perforator bed roller 18, is a drive shaft 42. Rotatably mounted on said drive shaft 42 is a tubular shaft 43 upon which are fixed bracket members 44 for supporting radially projected perforator blades 45, which when revolved, cooperate with said perforator bed roller 18 to laterally perforate the paper web 16 as it moves over the perforator bed roller 18 and beneath said revolved perforator blades.

Pivotedly mounted upon bearing lugs 46 connected with the front sides of said standards or end frame members 11 are swinging arms 47 between the lower free ends of which is rotatably supported a tension roller 48, said arms 47 and the roller 48 being yieldably held under tension against the paper web 16 as it pays off of the delivery roller 15 by pull springs 49 interconnected between the upper end of said arms 47 and the standards or end frame members 11.

Secured upon one of the standards or end frame members 11 is a housing 50 adapted to enclose the power transmission mechanism whereby operative movement is imparted to the various mechanisms making up the machine. Journaled in a bearing 51 connected with said housing 50 is a spindle 52 which is axially alined with said drive shaft 42 but rotatable independently thereof. Fixed upon the outer end of said spindle 52 is a driving pulley 53, or power may be applied to said spindle in any other way found desirable. Connected with the inner end of

said spindle 52 is a fixed driving clutch element 54. Keyed upon the adjacent end of said drive shaft 42 is a shiftable clutch element 55 which is engageable with said driving clutch element 54 when it is desired to couple said shaft 42 in driven relation to said spindle 52. Fixed on the opposite end of said shaft 42 is a spur gear 56 which meshes with a larger gear 57 fixed on the adjacent 10 end of the perforator bed roller shaft 17, and also fixed on said latter shaft 17 is a spur gear 58 which meshes with a spur gear 59 of similar size fixed on the adjacent end of the tubular shaft 43 carrying the perforator blades 45 and their supports. The above described arrangement of gears provides a speed reduction gearing for driving the perforator bed roller 18 and the perforator blades 45 harmoniously from said 20 drive shaft 42. The combined feed and guide roller 21 is driven by a spur gear 60 which is fixed upon an end of its shaft 20 so as to mesh operatively and be driven by the spur gear 58. Fixed on a journal 26' of 25 said slitting bed roller 26 is a spur gear 61 which meshes with and is driven by said spur gear 58. Fixed on a journal 22' of said upper winding roller 22 is a spur gear 62 which meshes with and is driven by said 30 spur gear 61, and, in like manner, fixed on a journal 23' of said combined winding and slitting roller 23 is a spur gear 63 which also meshes with and is driven by said spur gear 61. Fixed on a journal 30 of said combined winding and gate roller 24 is a spur gear 64, and rotatably mounted on an end of 35 said rock shaft 27 is an idler gear 65 which intermeshes with and between said spur gear 63 of the winding and slitting roller 23 and the spur gear 64 of the winding and gate roller 24. From the above description and 40 an inspection of Figure 4 of the drawings it will be apparent that the three winding rollers 22, 23, and 24 will be rotatably driven at the same speed and in the same direction 45 through the train of intermediate transmission gearing thus above described.

Rotatably mounted within said housing 50 is a cam drum 66 provided at its outer 50 end with worm gear member 67 for turning the same. Said cam drum is rotated through said worm gear member 67 by means of a transmission mechanism driven from said power spindle 52; said transmission mechanism comprises a driven bevel gear 68 connected with said power spindle 52 which meshes with a driven bevel gear 69 mounted upon a bearing shaft 70 suitably supported within said housing. 55 Rotatably mounted on said bearing shaft 70 is a sleeve 71 having a worm 72 which meshes operatively with said worm gear member 67. Connected with the end or hub of said driven bevel gear 68 is a fixed driving clutch member 73. Keyed upon the adjacent 60 clutch member 73 is a shiftable clutch member 74 which is engageable with said driving clutch member 73 so as to transmit rotary motion to said sleeve 71 and its worm 72; a clutch shaft lever mechanism 75 cooperates with said shiftable clutch member 74 the same being operated by a hand lever 76 on the upper exterior side of said housing 50.

70 Pivottally mounted within said housing 50 is a clutch shift lever mechanism 77 which operatively engages said shiftable clutch element 55, the same having at its free end an anti-friction roller 78 engageable by shift cam projections 79 and 80 which are fixed 80 upon and actuated by said cam drum 66 for the purpose of engaging and disengaging the paper web feeding mechanism at desired predetermined times, as will be hereinafter more particularly set forth.

85 Also mounted upon and actuated by said cam drum 66 is a gate roller actuating cam member 81 which cooperates with the anti-friction roller 32 of the lever arm 31.

90 Also fixed to the inner end of said cam drum 66 is an outwardly projecting stud 82 which is carried by the rotation of the cam drum into actuating engagement with tripper starwheel 41 of the tube feeding mechanism.

95 Supported for longitudinal extension between the standards or end frame members 11 in convenient position is an air pipe 83 having extending therefrom at suitable intervals air nozzles 84 which extend rearwardly beneath said combined winding and slitting roller 23, with their discharge ends leading upwardly into the space intermediate the winding and slitting roll 23 and the winding and gate roller 24. In like 100 manner, supported for longitudinal extension between the standards or end frame members 11 in convenient position is another air pipe 85 having extending therefrom at suitable intervals air nozzles 86 which extend forwardly above said combined winding and gate roller, with their discharge ends leading into the space intermediate the winding and gate roller 24 and the upper winding roller 22. The said air 105 pipes 83 and 85 are respectively connected by suitable hose or pipe conduits 87 and 88 with the discharge side of an air-control valve 89 mounted on the rear side of said housing 50. A supply-pipe 90, leading from a suitable supply of air under pressure communicates with said air control valve 89. Said air control valve 89 is provided with a pivoted actuating lever 91 for opening the same. Pivottally mounted on the rear of said housing 50 is an air valve trip lever 92 in engagement with said actuating lever 91, said trip lever 92 having an extension 93 with which is engaged a pull spring 94 for actuating said trip lever 92 when the 110 115 120 125 130

same is freed for operative movement. Said trip lever 92 is provided with a tail piece 95 which projects into the interior of said housing 50 so as to engage the circumferential surface of said cam drum 66, the same having an anti-friction roller 96 which rides on the cam drum surface. An opening 97 is provided in the wall of said cam drum, which is carried by the rotation of the latter opposite the tail piece 95 so as to free at such time, the trip lever 92 for actuation by the spring 94 to thereby operate the actuating lever 91 to open the valve for the delivery of air through the air nozzles 84 and 86 at desired predetermined times.

In accordance with the present invention means are provided for breaking away or separating the paper wound tubes or rolls from the runs of the paper web 16, when a desired predetermined length of paper has been wound on the tubes, preparatory to releasing such paper wound tubes or rolls from the machine. This severing or breaking means comprises a fixed carrier bar 98 mounted to extend longitudinally between said standards or end frame members 11 above said upper winding roll 22. Carried by said carrier bar 98 so as to be capable of vertical reciprocation are a series of breaker members 99 having upwardly projecting stems 100, adjacent to the upper free ends of which are fixed collars 101, and between said collars 101 and the upper side of said carrier bar are compression springs 102 which normally hold said breaker members in upwardly retracted or normally inoperative position. Said upper winding roller 22 is cut away to provide annular grooves 103 permitting the downward projection of said breaker members past the roll, and said breaker members are each provided at their lower free ends with a rearwardly turned foot portion 104. Journaled in and extending between said standards or end frame members 11 is a rock shaft 105, and fixed on said rock shaft 105 are a series of depressor levers 106 the free ends of which are adapted to respectively swing downwardly upon the upper portions of said breaker members, when said rock shaft is actuated, to operatively depress the same. The means for actuating said rock shaft 105 and its depressor levers 106 comprises a lever arm 107 which is fixed upon an end of said rock shaft which extends into said housing 50. Carried on the free end of said lever arm 107 is an anti-friction roller 108 which lies in the path of movement of a cam projection 109 fixed on said cam drum 66.

In accordance with the present invention means are also provided for applying adhesive to the free end of the paper wound upon the tube, so that after the wound roll is separated from the run of paper, said free

end of the paper roll may be glued down to the body of the roll and thus hold the wound paper from unwinding. This adhesive applying means comprises, in one form, a series of glue or paste reservoirs 110 supported from said carrier bar 98, the same having nozzles 111 extending downwardly from their lower ends. Extending through each reservoir and its nozzle is a vertically movable dauber or plunger 112 having a stem 113 projecting upwardly above the reservoir. Said dauber or plunger 112 is normally maintained in raised position by means of a compression spring 114 disposed on the stem 113 between a guide block 115 and a collar 116 which is fixed on the upper free end of said stem 113. The nozzles extend downwardly toward the combined winding and slitting roll 23, being spaced slightly above the surface of the latter. When the stem 113 is in normal raised position the dauber or plunger 112 shuts the mouth of the nozzle against the outward flow of glue or paste therefrom (as shown in Figure 8;) when, however, the stem 113 is depressed, the dauber or plunger moves downwardly out of the mouth of the nozzle, to thereupon permit an ejection or downward flow of glue or paste upon the paper passing over the winding and slitting roller 23, so that just prior to the breaking of the paper from the main run or web 16, the glue or paste will be applied thereto behind the breaking points, whereupon the final winding movement will press the glue or paste-provided free end of the paper to the main body of the wound roll (as shown in Figure 9). The means for producing a timely depression of the stems 113, for the above stated purposes, comprises a rock shaft 117, journaled in and extending between said standards or end frame members 11, with one end projecting into said housing 50. Fixed on said rock shaft 117 are depresser cam devices 118 for respectively engaging the upper ends of the stems 113 when the rock shaft is actuated. The means for producing a properly timed oscillation of said rock shaft 117 comprises a lever arm 119 fixed on the end of the rock shaft located within said housing 50 so as to be engageable by the cam projection 109 of said cam drum 66 in advance of the cooperation of the said cam projection 109 with the breaker mechanism.

Extending beneath the group of winding rollers is a chute or receiving trough 120 into which the paper wound tubes or rolls may fall when released from the said winding rollers.

Having thus described the general construction of the machine and its device and parts, I will now briefly describe the operation of the same.

For the purpose of illustrating the opera-

tion of the machine I will assume that a delivery roll 15 of paper sixty inches wide is mounted on the mandrel 14. The web 16 is carried from the delivery roller 15 over the tension roller 48, thence under the combined feed and guide roller 21 and over the perforator bed roller 18, and thence under the slitting bed roller 26 and over the combined winding and slitting roller 23. 5 The winding and gate roller 24 having swung open a tube 38 is positioned against the upper winding roller 22 and combined winding and slitting roller 23, whereupon the winding and gate roller is permitted to 10 close to normal initial position so that said tube is engaged at three points by and thus supported within the center of the group of winding rollers, all as illustrated in Figure 2. Power is now applied through the 15 pulley 53 to the spindle 52, and the clutch mechanism driving the worm 72 being operated to connect the latter through the bevel gears 69 and 68 with the power spindle 52, said worm 72 is rotated to in turn drive 20 the cam drum 66 through the worm gear 67, whereupon said cam drum 66 is rotated in the direction of the arrow shown in Figure 7. As the cam drum rotates the "throw-in" cam projection 79 is carried into operative engagement with the anti-friction 25 roller 78 of the shift lever mechanism 77 to engage the shiftable clutch element 55 with the fixed clutch element 54 of the power spindle 52, whereupon the drive 30 shaft 42 is rotated to in turn rotate the paper feeding perforator and the winding mechanisms. When the paper feeding perforator and winding mechanisms are thus set in motion, they operate to draw off the 35 web 16 from the delivery roll 15, and thence advance the web 16 to pass intermediate the tube 38 and the winding rollers 22, 23, and 24. As the end of the web 16 leaves the winding roller 23, the opening 97 is timed by 40 the rotation of the cam drum 66 to register with the tail piece 95 of the air valve trip lever 92 so that the same is momentarily freed for operation whereby the air control valve 89 is opened while the web 16 is entering 45 the winding rolls to permit blasts of air to be delivered from the nozzles 84 and 86 to thereupon press the entering end of the web toward the tube 38 so that its entrance between the same and the winding 50 rollers 24 and 22 is assured until it is caught and firmly held for rotation with the tube by the first convolution, after which the air is cut off. Since the winding rollers 22, 23, and 24 all turn at equal speeds in the same 55 direction, a rotary motion is imparted to the tube 38 and the paper so that the latter will be reeled or wound upon the tube. As the web 16 passes over the perforator bed roller 18 the perforator blades are rotated to intermittently strike the paper to form 60 therein lateral lines of perforations at longitudinal intervals equivalent to the length of one half the circumference of the bed roller 18, as will be understood from an inspection of Figure 2 of the drawings. Since 70 the paper web 16 is sixty inches wide and the tube 38 equally long and it is desired to produce ultimate wound tubes or rolls fifteen inches long, the run of the paper web 16 must be slit longitudinally at fifteen 75 inch intervals and the tubes also cut or scored transversely at similar intervals for ultimate separation of the parts thereof receiving the runs of reduced width. These operations are accomplished when the paper 80 passes over the combined winding and slitting roller 23; to this end the annular cutting blades 25 thereof are set fifteen inches apart, and serrated edges of the same will penetrate and cut longitudinally through 85 the paper, while at the same time laterally scoring the tube 38 while the first turns of paper are being taken up thereon. In the above described manner the paper is continuously fed to and wound upon the tube 90 until a desired length of paper is accumulated upon the tube. As the diameter of the roll of paper formed on the tube enlarges, the winding and gate roller 24 being yieldably mounted, yields outwardly without loosing its operative engagement therewith. Just prior to the time the completion of the desired accumulation of paper on the tube is accomplished, and immediately before the feeding movement of the paper 95 is stopped, the cam projection 109 is carried by the rotation of the cam drum 66 into passing engagement with the lever arm 119, whereby the rock shaft 117 is turned to swing the cam arms 118 down upon the 100 stems 113 of the paste delivery devices. As the stems 113 are depressed the daubers or plungers 112 are lowered from the mouths of the nozzles 111, thus liberating the paste so that the same may drop upon the paper 105 to form small spots adjacent to each side or end of the roll, after which the rock shaft and its cam arms return to normal initial position when the lever arm 119 escapes from the cam projection 109, thus permitting the stems 113 and daubers or plungers 112 to also resume normal position to close the nozzles 111 of the paste reservoirs. The winding of the paper on the tube continues 110 until the pasted portions are carried against the body of the formed roll to adhesively secure the ultimate free end of the roll to the body thereof. By the time the winding and pasting operations are completed, the "throw-out" cam projection 80 is carried 115 by the rotation of the cam drum into engagement with the anti-friction roller 78 of the shaft lever mechanism 77 whereby the latter is swung in an opposite direction to release the shiftable clutch-element 55 120 125 130

from the fixed clutch element 54, thereby stopping the rotation of the drive shaft 42 and consequently stopping the rotation of the paper feed, perforator and winding mechanisms, thus holding the paper web 16 motionless. As soon as the paper web 16 is thus brought to rest, the cam drum 66 carries the cam projection 109 into operative engagement with the anti-friction roller 108 of the lever 107 thereby rocking the rock shaft 105 to depress the breaker or ejector members 99, the feet 104 of which are forced downwardly upon the wound tube or roll, exerting a downward pressure thereon which breaks the runs of the web 16 along lines of perforations adjacent to the completed wound tube or roll of paper, to thereby separate the latter from the former. As this operation takes place, the cam drum 66 also carries the cam member 81 into engagement with the anti-friction roller 32 on the arm 31 to swing down the same and thereupon swing to open position the combined winding and gate roller 24, whereupon the separated wound tubes or roll of paper may drop down between the winding rollers 23 and 24 into the receiving chute or trough 120. While the winding and gate roller 24 is opened, the star detent wheels 40 are partially rotated to release another tube 38 from the stacker frame 37 to pass between the upper winding roll 22 and the winding and gate roller 24 before the breaker members 99 rise, so that as the latter resume normal raised position and the winding and gate roller 24 swings back to normal position, the new tube will be carried into operative relation to the group of winding rollers ready to receive the paper to be fed thereto and wound thereon. By the time the new tube is thus properly positioned and the breaker members and combined winding and gate roller resume normal initial positions, the "throw-in" cam projection 79 again engages and operates the shift lever mechanism 77 to operate the clutch devices serving to couple the drive shaft 42 with the spindle 52 so that the paper feed, perforator and winding mechanisms resume operative movement, and the operations above described are repeated. The machine may be thus run continuously until the supply of tubes and paper web 16 are exhausted.

55 The product of the machine consists of the wound rolls R of paper carried on a tubular or other core 38, the paper being provided at intervals throughout its length with lateral rows of perforations P, thus forming convenient separable sheets, which may be detached from the main body of the roll at the will of the consumer (see Figure 10).

60 The rolls thus produced may be made up of various kinds of paper suitable for va-

rious uses, such as waxed paper for lunch wrapping, paper for towels, for napkins, and paper for many other purposes.

I claim:

1. In a web-winding machine the combination of winding means, means for feeding a web to the winding means, means for arresting the winding and feeding means when the desired length of material has been wound, and means acting automatically and in synchronism with the feeding and winding means for severing the wound roll from the web. 70

2. In a web-winding machine the combination of winding means, means for feeding a web to the winding means, means for arresting the winding and feeding means when the desired length of material has been wound, and a breaker member bearing against the wound roll to sever the web and eject the wound roll from the machine. 80

3. In a web-winding machine the combination of winding means, means for feeding a web to the winding means, means for applying adhesive to the web when the desired length of material has been wound, and means for severing the web just after the adhesive-coated area of the web has contacted with the wound roll. 90

4. In a web-winding machine the combination of winding rollers designed to support and rotate a roll, feeding means designed to feed a web to the roll, means for arresting the winding rollers and feeding means when the desired length of material has been wound, means for removing one of the rollers from supporting position, and means for severing the web to eject the wound roll from the machine. 95

5. In a web-winding machine the combination of winding rollers designed to support and rotate a core, feeding rollers designed to feed a web to the core, means for arresting the rotation of the winding and feeding rollers when the desired length of material has been wound, means for swinging one of the winding rollers out of supporting position, and a breaker member designed to bear against the wound roll, sever the web and eject the wound roll from the machine. 105

6. In a web-winding machine, the combination of winding rollers designed to support and rotate a roll, feeding means designed to feed a web to the roll, means for perforating the web transversely, means for arresting the winding rollers and feeding means when the desired length of material has been wound, means for removing one of the rollers from supporting position, and means for severing the web along a perforation to eject the wound roll from the machine. 120

7. In a web-winding machine the combination of winding rollers designed to sup- 130

- port and rotate a roll, feeding means designed to feed a web to the roll, means for applying adhesive to the web at substantially the end of the winding operation, means 5 for arresting the winding rollers and feeding means as soon as the adhesive-coated part of the web has contacted with the wound roll, and means for ejecting the wound and pasted roll from the machine.
- 10 8. In a web-winding machine the combination of winding rollers designed to hold and rotate a core, feeding rollers designed to feed a web to the core, means for perforating the web transversely, a reciprocatory breaker or ejector member mounted adjacent the core, and means acting when a predetermined length of material has been wound, to arrest the rotation of the winding and feeding rollers, means for swinging one 15 of the winding rollers into non-supporting position, and means for moving the ejector member into contact with the wound roll to sever the web along a perforation and eject it from the machine.
- 20 9. In a web-winding machine the combination of winding rollers designed to hold and rotate a core, feeding rollers designed to feed a web to the core, a container for adhesive mounted above the web adjacent the core having a normally closed discharge opening, means for severing a wound roll from the web and ejecting it from the machine, and means for opening the discharge opening in the adhesive container and depositing adhesive on the web just prior to 25 severing the web.
- 30 10. In a web-winding machine the combination of winding rollers designed to hold and rotate a core, feeding rollers designed to feed a web to the core, means for perforating the web transversely, a reciprocatory breaker or ejector member mounted adjacent the core, a container for adhesive mounted above the web adjacent the core having a normally closed discharge opening, means acting when a predetermined 35 length of material has been wound to open the discharge opening in the adhesive container and deposit adhesive on the web, means for arresting the rotation of the winding and feeding rollers as soon as the adhesive coated area of the web contacts with the wound roll, means for swinging one of the winding rollers into non-supporting 40 position, and means for moving the ejector member into contact with the wound roll to sever the web along a perforation and eject it from the machine.
- 45 11. In a machine of the kind described, a pair of standards, means on said standards for rotatably mounting a delivery roll of paper web, a perforator bed roller journaled in and extending between said standards, a rotatable perforator means having 50 radially projecting perforator blades jour-
- naled in and extending between said standards above and so as to cooperate with said perforator bed roller, a combined feed and guide roller journaled in and extending between said standards for disposition forward of and cooperation with said perforator bed roller, a paper web tensioning means mounted on said standards for disposition intermediate said feed and guide roller and said delivery roller, said paper 55 web being led from said delivery roller over said tensioning means under said feed and guide roller and over said perforator bed roller, transmission means for rotating said perforator bed roller and said perforator 60 means, a group of winding rollers mounted between said standards and positioned in the rear of said perforator bed roller, said winding rollers being adapted to impinge upon a cylindrical core placed within the 65 same, and transmission means for rotating said winding rollers in the same direction to in turn rotate said core about its longitudinal axis, said paper web being adapted to pass from said perforator bed roller intermediate said winding rollers and said core 70 whereby said paper web is drawn from said delivery roller through the perforator devices and then wound on said core.
- 75 12. In a machine for winding paper on carrier tubes or cores, a group of winding rollers adapted to impinge upon a cylindrical core placed within the same, means for rotating said winding rollers in the same direction to in turn rotate said core about 78 its longitudinal axis, means for delivering a run of paper intermediate said winding rollers, and said core whereby said paper is wound upon the latter, means associated with said delivery means for transversely 80 perforating the paper at longitudinal intervals as it passes to said winding rollers, means for mounting one of said rollers for outward bodily movement, yieldable means opposing the outward movement of said 85 latter roller thus tending to normally hold the same in operative relation to the core and paper while the latter builds up on the former, said movable roller when outwardly moved permitting the removal of a paper 90 wound core from winding position and the insertion of a succeeding empty core into operative relation to said winding rollers, means for interrupting the operation of said 95 perforating and winding mechanisms when a predetermined amount of paper is wound upon said core, means for detaching the wound core from the run of paper feeding the same and ejecting the same from the 100 winding rollers, during the interruption of their operation, and means for applying adhesive to the last turn of paper to be wound on the core prior to the interruption of the winding operation.
- 105 13. In a machine for winding paper on 108

carrier tubes or cores, a group of winding rollers adapted to impinge upon a cylindrical core placed within the same, means for rotating said winding rollers in the same direction to in turn rotate said core about its longitudinal axis, means for delivering a run of paper intermediate said winding rollers and said core whereby said paper is wound upon the latter, means associated with said delivery means for transversely perforating the paper at longitudinal intervals as it passes to said winding rollers, means for mounting one of said rollers for outward bodily movement, yieldable means opposing the outward movement of said latter roller thus tending to normally hold the same in operative relation to the core and paper while the latter builds up on the former, said movable roller when outwardly moved permitting the removal of a paper wound core from winding position and the insertion of a succeeding empty core into operative relation to said winding rollers, means for interrupting the operation of said perforating and winding mechanisms when a predetermined amount of paper is wound upon said core, means for detaching the wound core from the run of paper feeding the same and ejecting the same from the winding rollers during the interruption of their operation, means for applying adhesive to the last turn of paper to be wound on the core prior to the interruption of the winding operation, and means for automatically shifting said bodily movable winding roller to open position to permit the ejection of the detached paper wound core from the winding rollers, and means for delivering an empty tube to the winding rollers while said bodily movable winding roller is in open position.

14. In a machine for winding paper on carrier tubes or cores, a group of winding rollers adapted to impinge upon a cylindrical core placed within the same, means for rotating said winding rollers in the same direction to in turn rotate said core about its longitudinal axis, means for delivering a run of paper intermediate said winding rollers and said core whereby said paper is wound upon the latter, means associated with said delivery means for transversely perforating the paper at longitudinal intervals as it passes to said winding rollers, means for mounting one of said rollers for outward bodily movement, yieldable means opposing the outward movement of said latter roll thus tending to normally hold the same in operative relation to the core and paper while the latter builds up on the former, said movable roller when outwardly moved permitting the removal of a paper wound core from winding position and the insertion of a succeeding empty core into operative relation to said winding rollers, means for interrupting the operation of said perforating and winding mechanisms when a predetermined amount of paper is wound upon said core, means for detaching the wound core from the paper web and ejecting the same from the winding rollers during the interruption of their operation, and means for applying adhesive to the last turn of paper to be wound on the core prior to the interruption of the winding operation.

15. In a machine for winding paper on carrier tubes or cores, a group of winding rollers comprising an upper roller, a forward lower roller and a rearward lower roller, normally spaced equidistant around and impinging upon a core centered intermediate the same, transmission means for simultaneously rotating said rollers in the same direction to in turn rotate said core about its longitudinal axis, means mounting said rearward lower roller for outward yieldable movement whereby the same serves additionally as a compensating and gate roller, means for feeding and guiding a run of paper for delivery intermediate said winding rollers and said core, means associated with said paper guiding means for transversely perforating the paper at longitudinal intervals, and said forward lower winding roller having longitudinally spaced annularly projecting slitting blades connected therewith, means for interrupting the operation of said perforating and winding mechanisms when a predetermined amount of paper is wound upon said core, means for detaching the wound core from the paper web and ejecting the same from the winding rollers during the interruption of their operation, and means for applying adhesive to the last turn of paper to be wound on the core prior to the interruption of the winding operation.

16. In a machine for winding paper on carrier tubes or cores, a group of winding rollers comprising an upper roller, a forward lower roller and a rearward lower roller normally spaced equidistant around and impinging upon a core centered intermediate the same, transmission means for simultaneously rotating said rollers in the same direction to in turn rotate said core about its longitudinal axis, means mounting said rearward lower roller for outward yieldable movement whereby the same serves additionally as a compensating and gate roller, means for feeding and guiding a run of paper for delivery intermediate said winding rollers and said core, means associated with said paper guiding means for transversely perforating the paper at longitudinal intervals as it passes to said winding rollers, means for mounting one of said rollers for outward bodily movement, yieldable means opposing the outward movement of said latter roller thus tending to normally hold the same in operative relation to the core and paper while the latter builds up on the former, said movable roller when outwardly moved permitting the removal of a paper wound core from winding position and the insertion of a succeeding empty core into operative relation to said winding rollers, means for interrupting the operation of said perforating and winding mechanisms when a predetermined amount of paper is wound upon said core, means for detaching the wound core from the paper web and ejecting the same from the winding rollers during the interruption of their operation, and means for applying adhesive to the last turn of paper to be wound on the core prior to the interruption of the winding operation.

upon said core, means for detaching the wound core from the run of paper feeding the same and ejecting the same from the winding rollers during the interruption of their operation, means for applying adhesive to the last turn of paper to be wound on the core prior to the interruption of the winding operation, means for automatically shifting said bodily movable winding roller to open position to permit the ejection of the detached paper wound core from the winding rollers, and means for delivering an empty tube to the winding rollers while said bodily movable winding roller is in open position.

15. In a machine for winding paper on carrier tubes or cores, a group of winding rollers comprising an upper roller, a forward lower roller and a rearward lower roller, normally spaced equidistant around and impinging upon a core centered intermediate the same, transmission means for simultaneously rotating said rollers in the same direction to in turn rotate said core about its longitudinal axis, means mounting said rearward lower roller for outward yieldable movement whereby the same serves additionally as a compensating and gate roller, means for feeding and guiding a run of paper for delivery intermediate said winding rollers and said core, means associated with said paper guiding means for transversely perforating the paper at longitudinal intervals, and said forward lower winding roller having longitudinally spaced annularly projecting slitting blades connected therewith, means for interrupting the operation of said perforating and winding mechanisms when a predetermined amount of paper is wound upon said core, means for detaching the wound core from the paper web and ejecting the same from the winding rollers during the interruption of their operation, and means for applying adhesive to the last turn of paper to be wound on the core prior to the interruption of the winding operation.

16. In a machine for winding paper on carrier tubes or cores, a group of winding rollers comprising an upper roller, a forward lower roller and a rearward lower roller normally spaced equidistant around and impinging upon a core centered intermediate the same, transmission means for simultaneously rotating said rollers in the same direction to in turn rotate said core about its longitudinal axis, means mounting said rearward lower roller for outward yieldable movement whereby the same serves additionally as a compensating and gate roller, means for feeding and guiding a run of paper for delivery intermediate said winding rollers and said core, means associated with said paper guiding means for transversely perforating the paper at longitudinal intervals as it passes to said winding rollers, means for mounting one of said rollers for outward bodily movement, yieldable means opposing the outward movement of said latter roller thus tending to normally hold the same in operative relation to the core and paper while the latter builds up on the former, said movable roller when outwardly moved permitting the removal of a paper wound core from winding position and the insertion of a succeeding empty core into operative relation to said winding rollers, means for interrupting the operation of said perforating and winding mechanisms when a predetermined amount of paper is wound upon said core, means for detaching the wound core from the paper web and ejecting the same from the winding rollers during the interruption of their operation, and means for applying adhesive to the last turn of paper to be wound on the core prior to the interruption of the winding operation.

tudinal intervals, said forward lower winding roller having longitudinally spaced annularly projecting slitting blades connected therewith, means for interrupting the operation of said perforating and winding mechanisms when a predetermined amount of paper is wound upon said core, means for detaching the wound core from the paper web and ejecting the same from the winding rollers during the interruption of their operation, and means for replacing the ejected wound core with an empty core.

17. In a machine for winding paper on carrier tubes or cores, a group of winding rollers comprising an upper roller, a forward lower roller and a rearward lower roller normally spaced equidistant around and impinging upon a core centered intermediate the same, transmission means for simultaneously rotating said rollers in the same direction to in turn rotate said core about its longitudinal axis, means mounting said rearward lower roller for outward yieldable movement whereby

the same serves additionally as a compensating and gate roller, means for feeding and guiding a run of paper for delivery intermediate said winding rollers and said core means associated with said paper guiding means for transversely perforating the paper at longitudinal intervals, and said forward lower winding roller having longitudinally spaced annularly projecting slitting blades connected therewith, means for interrupting the operation of said perforating and winding mechanisms when a predetermined amount of paper is wound upon said core, means for detaching the wound core from the paper web and ejecting the same from the winding rollers during the interruption of their operation, and means for applying adhesive to the last turn of paper to be wound on the core prior to the interruption of the winding operation, and means for replacing the ejected wound core with an empty core.

In testimony whereof I affix my signature.
NICHOLAS MARCALUS.
